Primary Examiner — Michelle E. Wilson*Assistant Examiner* — Charles Hwang(74) *Attorney, Agent, or Firm* — Boyle Fredrickson, S.C.(57) **CLAIM**

The ornamental design for a backup battery pack as shown and described.

DESCRIPTION

FIG. 1 is a bottom, front, right-side isometric view of a backup battery pack showing our new design;

FIG. 2 is a bottom plan view thereof;

FIG. 3 is a top plan view thereof;

FIG. 4 is a right-side elevation view thereof;

FIG. 5 is a left-side elevation view thereof;

FIG. 6 is a front-side elevation view thereof;

FIG. 7 is a rear-side elevation view thereof; and,

FIG. 8 is a top, front, right-side isometric view thereof.

The broken lines represent unclaimed portions of the design. All of the broken lines form no part of the claimed design.

1 Claim, 8 Drawing Sheets(56)
